UNITED STATES PATENT OFFICE.

WESTON M. FULTON, OF KNOXVILLE, TENNESSEE, ASSIGNOR TO THE FULTON COMPANY,
OF KNOXVILLE, TENNESSEE, A CORPORATION OF MAINE.

FLUSH-TANK.

1,203,106.

Specification of Letters Patent. Patented Oct. 31, 1916.

Application filed February 20, 1913. Serial No. 749,866.

To all whom it may concern:

Be it known that I, WESTON M. FULTON, of Knoxville, Tennessee, have invented a new and useful Improvement in Flush-Tanks, 5 which invention is fully set forth in the following specification.

This invention relates to improvements in flush tanks and particularly to the means for discharging the contents of the tank 10 for flushing purposes.

The primary object of this invention is to provide a device for discharging the flush tank which will enable all forms of valves for controlling the outlet to the flushing 15 pipe to be dispensed with.

A further object of the invention is to simplify and cheapen the construction of the discharge controlling means of flush tanks while insuring certainty of operation 20 and durability of the parts.

Heretofore it has been generally customary to control the outlet from the flush tank by means of a rubber ball which is either solid or hollow. This ball is arranged to 25 seat itself on the end of the flushing pipe leading from the tank to the hopper and is held therein by the weight of the water above it until it is desired to discharge the tank when the ball is lifted by suitable 30 means to allow the water to escape into the flush pipe. The ball then floats at the surface until the tank is emptied when it seats itself on the top of the flush pipe and is held there by the water admitted by the automatic 35 valve controlling the water supply. Serious objections arise to the use of rubber valves under the conditions existing in these tanks. Under the combined influence of the water and variations of temperature, the 40 solid rubber balls become hard and brittle and refuse to shut off the escape of water. While this loss of water is serious enough in itself, the flushing operation is rendered imperfect and the noise caused by the escape of 45 water into the flushing pipe is transmitted over the entire system of water pipes in the house and becomes annoying. Hollow rubber balls have their own peculiar defects in becoming collapsed. They then refuse to

50 float and also to seat properly. Attempts have been made to replace rubber ball valves by siphon valves, but these valves, like all seating valves, are subject to seating defects such as result from defective fitting and

from sedimentary deposits lodging between 55 the valve and seat, thereby causing leakage.

Flush tanks have also been provided with siphons having a flexible connection between the discharge pipe of the tank and one end of the bent section of the siphon, this connection being made of rubber or of annular disks united at their exterior and interior peripheries to form a tubular wall similar to a Japanese lantern. The objections explained above as to rubber valves applies to 60 rubber connections. The metal disk type of flexible connection requires the annular disks to be wide and of large outside diameter to give flexibility to the connection. The deep 65 folds in the connection receive and retain sediment from the standing water and after a time the tank becomes foul and unsanitary. These connections are necessarily bulky, displace considerable water and necessitate the 70 use of a tank larger than necessary. They are uncertain in their action both in filling and discharging because of the depth of the recesses in their walls and their converging 75 shape.

My invention overcomes the above objections and secures the objects above described, and resides in providing the flush tank with a siphon having one branch adapted to be permanently connected to the flushing pipe through a flexible conduit, preferably made 80 of flexible corrugated metal tubing, and having the other branch free to be raised or lowered by means operable from outside the tank. The siphon in its preferred form consists of a bent tube with plain walls made of 85 non-corrodible metal such as copper or brass to one branch of which is secured a flexible corrugated brass or copper tube which is permanently connected to the end of the flushing pipe. Means are provided for normally keeping the bend of the siphon above 90 the normal water level in the tank, the object being to have an air space in the bend to prevent continued siphon action when flushing is not required. Such means may 95 consist of a weighted lever or its equivalent, a spring. I prefer, and in practice use a weighted lever for this purpose.

In order that the invention may be readily understood, reference is had to the accompanying drawings forming part of the specification, illustrating one constructional form embodying my improvement; but such

drawings are designed for illustration only and are not intended for the purpose of defining the limits of the invention.

In the drawings:—Figure 1 is a view in perspective of a flush tank provided with my improvements, and Fig. 2 is an enlarged view in central vertical section through a flush tank showing my improvements in connection therewith.

10 In Fig. 1 is illustrated the conventional form of flush tank 1 secured to the wall of a bath room and 2 is the hopper connected through flushing pipe 3 with the tank 1. Water is supplied to the tank by means of 15 a supply pipe 4 having its delivery end within the tank and controlled by a float operated valve 5 of the ordinary type, (see Fig. 2). The tank is provided with the usual copper lining 6 which slightly sets away 20 from the tank wall at 7 to form a guide passage for an operating rod 8. The structure, above described, is old and may be of any known construction.

Through an opening 9 in the bottom of 25 the flush tank 1, I insert a discharge pipe 10 which is secured in place by clamping nuts 11 and is joined to the flush pipe 3 in any suitable manner. To the opposite and upper end of the discharge pipe 10, I connect 30 a bent tube 13 by means of the flexible corrugated metal tube 12 which is soldered or otherwise made secure to the discharge pipe. The corrugations in the flexible tube are of requisite number, depth and spacing 35 to permit the bend in the tube to sink well under the normal water level in the tank to enable filling and siphoning action. A lug 14 is provided on the bent tube for connecting with a link 15 which is jointed to the 40 long arm of a lever 16 pivoted at 17 on the wall of the tank. The short arm of the lever supports a sliding weight 18 adapted to counterpoise the weight of the bent tube 15 and normally keeps it in elevated position 45 as shown in the drawing. The short arm of the lever is also connected to an operating knob 19 located in convenient position outside the tank through a rod 8.

The operation of the device is as follows: 50 Assuming the flush tank filled to the water line and the valve 5 closed by operation of the float, the knob 19 is raised. The long arm of the lever 16 is thereby depressed and forces the bent tube 13 below the water line. 55 Water then fills the tube 13 beyond its bend and the tank begins to discharge through the

flush pipe 3. Momentary lifting of knob 19 is sufficient to start siphoning. Release of the knob 19 restores the parts to their normal position, but the discharge from the tank continues as will be readily understood from the principles governing the action of siphons. When the water level sinks below the receiving end of the bent tube, air enters and the action discontinues. The tank then 60 refills under the automatic opening of the supply valve 5 until the water line is reached and the tank is ready for the next flushing operation.

From what has preceded, it will be evident that my improved siphon attachment overcomes the objections inherent to the use of rubber valves by dispensing with their use and it also obviates the difficulties accompanying the seating of metal valves on 75 the end of the flush pipe, due to sedimentary deposits. The flexible metal connection in the siphon resists the action of water and varying temperatures and affords no chance for sediments to interfere with its operation 80 because of the rounded corrugations and freedom of sharp angles and seams in the connecting sections.

While I have shown the flexible section midway of the longer member or leg of the siphon, I do not desire to be restricted to this location, as it is obvious that the section may be directly attached at the bottom opening in the tank. The position shown is preferable for the reason that a shorter 90 length of corrugated pipe is required while giving the necessary extent of movement to the free end of the siphon; and further the siphon may be made entirely of flexible corrugated metal tubing and secure the advantages of my improvement, but such construction unnecessarily adds to the cost and I, therefore, prefer the embodiment shown.

What is claimed is:—

In combination, a flush tank having a discharge pipe, a siphon in said tank, a flexible corrugated metal tube connecting the siphon with said discharge pipe, and means for flexing said connection to fill the siphon and discharge said tank.

In testimony whereof I have signed this specification in the presence of two subscribing witnesses.

WESTON M. FULTON.
